UNITED STATES PATENT OFFICE.

JOHN C. SHERRY, OF SEATTLE, WASHINGTON, ASSIGNOR TO SHERRY WATER TUBE
BOILER CO., OF SEATTLE, WASHINGTON, A CORPORATION OF WASHINGTON.

STEAM-BOILER.

1,304,392.

Specification of Letters Patent. Patented May 20, 1919.

Application filed May 1, 1918. Serial No. 231,790.

To all whom it may concern:

Be it known that I, JOHN C. SHERRY, a citizen of the United States, residing at Seattle, in the county of King and State 5 of Washington, have invented new and useful Improvements in Steam-Boilers, of which the following is a specification.

This invention relates to steam boilers or generators.

- 10 One of the objects of the present invention is to provide a boiler, consisting of an upper steam drum and a pair of lower, interspaced circulating drums which are connected with the steam drum by means of a front and a rear header, said headers being in turn connected by a series of staggered, inclined heating tubes, and said steam drum being connected with the lower circulating drums by means of a series of vertically disposed circulating tubes to permit a return circulation between the steam drum and the lower circulating drums and an upward circulation through the headers and the heating tubes carried thereby.
- 15 Another object of the invention is to connect the lower circulating drums with a combination blow and feed drum to permit an even distribution of the incoming feed water and to permit collection and removal 20 of sediment whenever desired.

Another object of the invention is to eliminate as much as possible the employment of stay bolts and bracing members of any nature, and to arrange the vertical circulating 25 tubes on each side of the furnace chamber to increase the heating area exposed to the furnace.

Another object of the invention is to provide a novel means for staggering and supporting the heating tubes to permit a free 30 upward circulation, and to permit an even exposure of said tubes to the heat of the furnace.

Further objects will hereinafter appear. 35 The invention consists of the parts and the construction and combination of parts, as hereinafter more fully described and claimed, having reference to the accompanying drawings, in which—

40 Figure 1 is a side elevation of the boiler partly in section.

Fig. 2 is an end view of same, partly in section.

Referring to the drawings in detail, A indicates a steam drum and 2 and 3 a pair of

lower circulating drums arranged one at each side of the boiler. Connecting the steam drum with the lower circulating drums 2 and 3 in a front header 4 and a rear header 5. The upper end of each header is directly connected to the lower half of the steam drum, while the lower end of each header is connected to the lower circulating drums, as shown at 6 and 7, respectively.

60 Forming a connection between the headers is a series of inclined heating tubes, nested above each other in two tiers, as indicated at 8 and 9. The tubes forming the lower set are staggered in relation to each other and they are also inclined in opposite directions. One row of tubes is connected at its lower end with the front header, as at 10, while its upper opposite end is connected with the rear header, as at 11. The complementary set of tubes is connected at its lower end with the rear header, as at 12, while its upper opposite end is connected, as at 13, with the front header. The respective tubes 65 must necessarily be staggered, as shown at 14, 15 and 16, to pass each other, and, due to their inclination, always permit water to 70 freely circulate in an upward direction from the lower circulating drums through the steam drum.

75 There are two sets of nested tubes, as previously stated, and they are both connected with the front and rear headers, respectively, as shown. The two sets of tubes are, of course, exposed directly to the products 80 of combustion and an even distribution of the products of combustion is obtained by placing a baffle plate 17 between the upper and lower nested sets of tubes; that is, heat produced by a fire passing over or supported 85 by the grate bars shown at 18 will pass in an upward direction between the lower set of tubes 8 toward the rear header. It will then pass in a forward direction, as indicated by the arrows, over the baffle plate 17 and between the upper set of tubes 9, being finally permitted to escape through short flues or smoke tubes 19 placed in the upper portion 90 of the front header into the bridging 20 which forms a part of the front sheeting of 100 the boiler. The bridging or flue is divided at this point so that it may pass upwardly and around the steam drum, as at 21, directly into a stack 22.

105 The smoke flues 19 are shown in Figs. 1 110

and 2 as being staggered in relation to the tubes 9, the respective rows of smoke flues being shown at 19 while the oppositely inclined rows of tubes 9 are shown at 9 (see Fig. 2). The products of combustion or heat produced in the furnace chamber pass constantly in an upward direction and the circulation of water between the lower drums and the steam drum is also in an upward direction, thus permitting a free flow of water and steam between the lower drums and the steam drum. Return circulation is secured by providing two sets of vertically disposed tubes, such as shown at 22'. These are arranged on each side of the boiler exteriorly of the longitudinally extending heating tubes 8 and 9.

There is a double row of vertical tubes on each side of the boiler, such as shown at 22' and 23, the tubes on one side being connected at their lower ends with the drum 2 and at their upper ends with the steam drum A; the opposite set of vertical tubes being connected with the lower drum 3 and at their upper ends with the steam drum A. A free circulation for returning water is thus maintained on each side of the boiler and an enormous additional heating area is at the same time obtained.

30 The steam drum may be provided with a series of baffle plates, such as shown at 25 and 26, to direct the returning water to the vertical tubes 22' and 23 and a baffle drum 27, slotted in its upper side, as at 28, may be provided for the escape of steam to be utilized through the steam drum saddle flange 29. The drum is otherwise provided with a front head 30 and a rear head 31, a surface blow-off nozzle 32, and a manhole plate 33. The shell of the drum is preferably constructed of two sections 34 and 35, the lower section being heavier, as shown, as it is constantly exposed to the heat of the furnace chamber.

45 For the purpose of permitting an even distribution of the feed water delivered to the boiler and also for the purpose of readily removing mud and sediment whenever desired, a combination feed and blow-off drum

50 40 has been provided. This drum is positioned crosswise of the boiler and is connected with the rear ends of the drums 2 and 3. This drum is provided with a feed nozzle 41 and a blow-off nozzle 42. This may be 55 opened in the usual manner from time to time when it is desired to blow off the boiler for the removal of sediment and the like. The feed water entering the nozzle 41 is divided into two streams as the drum 40 is 60 connected with the two lower drums 2 and 3. Water entering each of these drums passes endwise through the same and is again evenly distributed and divided to the front and rear headers, respectively, thus 65 providing an ideal system of circulating

and distributing the feed water delivered to the boiler.

The boiler as a whole may be inclosed by sheeting, as shown at 50, and heat-insulating material, such as asbestos or the like, 70 may be employed in connection with the same as in standard practice. Any suitable form of furnace may be employed; that is, either coal may be burned or oil burners may be inserted through the front doors 55. 75 As this does not form any important feature of the present invention more reference thereto is thought unnecessary.

By referring to the boiler in general, it can be seen that the only stay bolts required 80 are those which connect the front and rear plates of the headers. These stay bolts, as shown at 56, are staggered between the heating tubes, and as the inclined tubes 8 and 9 connect the front and rear headers, longitudinally extending bolts or bracing of any kind can be entirely eliminated.

Another feature of advantage is the enormous heating area obtained. First, it will 90 be seen that both the front and rear headers are directly exposed to the heat of the furnace chamber, as is also the lower half of the steam drum; second, an enormous area is obtained by placing the tubes 8 and 9 as shown; and, third, an additional area is obtained by placing the vertical return circulating tubes on each side of the boiler. Ideal circulation of the water is at the same time obtained and an added steaming capacity and efficiency in proportion to the 95 amount of fuel consumed are obtained when compared with other boilers. It, therefore, not only renders itself adaptable for marine use but also for stationary and other purposes.

I wish it understood that the hand-hole plates, such as shown at 60, may be placed in the front and rear headers in alignment with the tubes 8 and 9 to permit cleaning and expanding of said tubes and that the 100 materials and finish of the several parts forming the boiler may be such as the experience and judgment of the manufacturer may dictate.

Having thus described my invention, what 115 I claim and desire to secure by Letters Patent is—

1. In a steam generating boiler, a central upper steam drum, a pair of lower circulating drums arranged on opposite sides of and outwardly beyond the outer sides of the upper drum, a front and a rear header, said headers each having the sides of their upper ends contracted and said ends connected to the bottom of the upper drum and having 120 their lower corners connected to the lower drums, inclined heating tubes connected to the headers, and two series of vertical circulating tubes at each side of the boiler and forming sides for the latter, said series be- 125 130

ing each disposed beyond the heating tubes and at the sides of the headers and being arranged with one set in advance of the other and with spaces between the tubes of one set 5 with which spaces the tubes of the other set register, the circulating tubes each having their upper ends curved inwardly to correspond to the contraction of the header sides and having their lower ends connected to 10 the lower drums.

2. In a steam generating boiler, a central upper steam drum, a pair of lower circulating drums arranged on opposite sides of the upper drum, a front and a rear header, said 15 headers having their upper ends connected to the upper drum and their lower ends connected to the lower drums, inclined heating tubes connected to the headers, circulating tubes connected to the upper drum and to

the respective lower drums, a bridging disposed over the front face of the upper portion of the front header and extending outwardly from said front face of the upper header in spaced relation thereto to form a flue extending over the front face of the 25 front header, and smoke flues passing through the front and rear faces of the front header and extending into the flue provided by the bridging to enable the products of combustion to contact with and circulate 30 around the upper steam drum.

In testimony whereof I have hereunto set my hand in the presence of two subscribing witnesses.

JOHN C. SHERRY.
